BOILER WATER LINE INDICATING DEVICE

Joseph R. Guildford, Niagara Falls, Ontario,
Canada

Application January 12, 1944, Serial No. 517,936

6 Claims. (Cl. 73—296)

My invention relates to a boiler water line indicating device for high setting steam boilers and has for its primary object to provide means for determining the water line in a boiler at a point about eye level above the boiler room operating floor regardless of the height of the boiler.

The indicating means for determining the height of the water line in the boiler may be located at any point in the boiler room, or it may be located at any point remote from the boiler room. This indicating means may be located below or above the water line of the boiler in a separate building at any distance from the boiler room.

The impelling means of the device for operating the indicating means is designed for safety and is capable of withstanding any boiler pressures now developed or which may be developed. This impelling means has no parts to rupture due to boiler pressures and embodies a novel construction.

All of the foregoing and further objects and advantages of the invention will become apparent from a study of the following specification and the accompanying drawings wherein like characters of reference designate corresponding parts throughout the several views, in which:

Figure 1 shows a vertical view of the device with a cutaway section of a boiler drum in which the normal water line of the boiler is shown and is indicated.

Figure 2 is a vertical view of the device with a cut-away section of a boiler drum and a sectional view of the cylinder in which the low water line of the boiler is shown and is indicated.

Figure 3 shows a plan view of the device connected to the boiler drum but not showing the indicator or electric wiring.

Figure 4 is a vertical view of the impelling means on line 4—4 of Figure 3.

Figure 5 shows an enlarged vertical view of the electrical contactor panel.

Figure 6 shows an enlarged vertical end view of the electrical contactor panel, on line 6—6 of Figure 5.

Figure 7 shows an enlarged plan view of a contactor point.

Figure 8 shows an enlarged elevational view of a contactor point.

Figure 9 shows a sectional view of Figure 7 on line 9—9.

Figure 10 shows a vertical view of a portion of the rocker arm and terminal.

Figure 11 shows a plan view of the arm of Figure 10 with its contact.

Figure 12 shows a sectional view of Figure 11 on line 12—12.

Referring in detail to the drawings:

The numeral 13 indicates a hollow cylinder closed at the top and bottom with heads 14 and 15. Connected to the wall of the cylinder at 16 and 17 and providing access thereto are the end of each of the pipe coils 18 and 19. These coils are designed to provide flexibility.

The remaining ends of coils 18 and 19 are connected through unions 20 and valves 21 to the steam space 22 and water space 23 of the boiler drum 24 at 25 and 26. It will be obvious that since the pipe coils are connected to both the boiler drum and cylinder in the manner herein described and shown that any fluctuation of water within the boiler drum will correspondingly fluctuate within the cylinder and that boiler pressure will be existent in the pipe coils and cylinder. The weight of materials used in the construction of said cylinder, coils, valves and unions may correspond to such materials as designed to withstand such boiler pressures for which the boiler may be operated. It will therefore be clear that the impelling means of the device is safe from rupture and safety is assured at all times.

The valves 21 are for the purpose of isolating the device when necessary and the unions 20 are for connecting and disconnecting when desired.

The drawings indicate welded construction of the cylinder, coils, valves and unions but this construction may be by means of threaded or flanged joints as desired, and while the drawings show the coils direct-connected to the boiler drum it is to be understood that the coils may be connected indirectly to the steam and water spaces of the boiler through regular water column piping connections (not shown).

The numeral 27 indicates a structural channel and 28 indicates a cradle, both of which are supplied by others for supporting the boiler. 29 is a platform riveted or bolted to 27 to support one end of 29. The opposite end of 29 is supported with brackets 30 bolted to 29 at 31 and to the boiler brickwork designated as 32.

A cylinder supporting cradle 33 is mounted on 29 by welding or bolting at 34. Cradle braces 35 are provided and welded or bolted on 29 at 36. A spring 37 is provided for supporting the weight of the cylinder 13 and one end portion of each of the coils 18 and 19 at low water level position. An eye bolt 38 is mounted on the cylinder head 14 to which is attached one end of the spring 37. A threaded eye bolt 39 is adjustably mounted 55 to the cradle 33 by means of nuts 40. The re-

maining end of the spring 37 is attached to the eye bolt 39.

A bracket 41 is mounted on the cylinder head 15. 42 designates a bifurcated head mounted on a threaded extension 43 and is adjustably attached to 41 by means of nuts 44. The bifurcated head 42 is pivotally attached by a pin 45 to the rocker arm 46 at 47. 48 designates a bifurcated head mounted on a threaded extension 49 and adjustably attached to the platform 29 by means of nuts 50. The bifurcated head 48 is pivotally attached by a pin 51 to the rocker arm 46 at 52.

The rocker arm 46 is provided with holes at 47 and 52 for the pins 45 and 51 to pass through. One end of the rocker arm 46 is provided with an adjustable weight 53 which is fastened in position onto the rocker arm by means of a threaded set screw 54. This weight is for the purpose of counterbalancing the rocker arm on each side of the point 52.

The remaining end of the rocker arm is provided with a fork like portion 55. One of the arms of the fork is provided with a contact 56 comprising a copper flexible disk 57. The disk is mounted to the arm of the fork by an insulated plate 58 to which is attached a threaded bolt 59 and nut 60. An insulation washer 61 is provided to isolate the copper disk from the arm of the fork. On the disk is mounted a terminal 62 for attachment of an electric main wire 63. The remaining arm of the fork is provided at its end with a finger 64. The object of the finger is to maintain a slight pressure on the flexible disk in order to make a contact between the disk and a contact point or points on the contact or panel shown in Figure 5.

The platform 29 is provided with an extended apron 65 for the attachment of the contactor panel 66. Slotted openings are provided at 67 for adjustment of the panel 66. Bolts and nuts 68 are provided for attachment of the panel 66 to the apron 65. The contactor panel comprises two sides 69 and 70 and a spacer 71. The side 69 is preferably to be constructed of an insulating material and perforated to receive the contact points 72. The spacer 71 is also preferably to be constructed of an insulating material and slotted to receive the contact points 72. The sides 69 and 70 together with the spacer 71 are bolted together by means of flatheaded bolts 73 and nuts 74.

Flanges 75 are provided on the sides 69 and 70 and perforated at 76 for insertion of the bolts 68. Cavities 77 are provided in the ends of the contactor points 72 for insertion of the electric wires 78 where they can be sweated into place.

The numeral 79 designates the indicator and comprises a panel 80 on which is mounted a number of electric lamps in lamp sockets as at 81. Electric wires 78 shown diagrammatically are connected at one end to the contact points 72 and at their opposite ends to the lamp sockets in which the electric lamps are mounted. Perforations 82 are provided in the panel 80 for mounting the panel on a wall or gauge board. Electric wires 83 are connected to the lamp sockets at 81 and to the main electric wire 84. The electrical circuit for operating the lamps on the indicating panel is provided through wire 63, through the contact 56 and contact point or points 72, through the wiring 78, through the lamps at 81, through the wiring 83 and 84. The source of electric current to which 63 and 84 are to be attached is not shown.

The numerals 85 indicate rocker arm limits and

comprise threaded rods with nuts 86 for fastening into place. These rods pass through the contactor panel assembly 69, 70 and 71, and are provided to limit the movement of the rocker arm 46 from a low water level to a high water level position.

The disk 57 is to be made sufficiently large to make contact with an adjacent contact point on the panel before leaving the contact point it is moving away from. By this means there will always be a light showing on the indicator board.

In the event of possible electric power or lighting failure an operator will still be able to determine the water line in the boiler to which my device is attached by observing the position of the fork-like portion 55 of the rocker arm 46 on the contactor panel 66. This is important because try cocks usually furnished and installed on water columns to boilers are not shown or supplied with my indicating device, and some method must be provided to determine the water line. In other words, if a gauge glass on an ordinary boiler water column breaks the try cocks have to be relied on until a new gauge glass is installed. With my device, in the event of electric power or lighting failure the rocker arm position in relation to the contactor panel must be relied on to indicate the relative position of the boiler water line which is obvious.

Briefly, the operation of the invention is as follows:

In Figure 2 it will be noted that the water line is shown below the normal water line shown in Figure 1 indicating that a low water line exists. In this low water line condition the spring has drawn the cylinder up and the rocker arm fork portion 55 is down to its low limit making contact with the lowest contactor point causing electric current to flow through to the lowest lamp and lighting it on the indicator panel. As water is introduced into the boiler the weight of the column of water forming in the cylinder from the boiler causes the cylinder to lower and the spring to lengthen. As this movement takes place the rocker arm fork portion 55 moves upward causing a contact to be made at each succeeding contact point. As each contact point is reached the lamp on its circuit lights up and the lamp circuit contact point which the contact has left goes out. This action takes place successively as the water flows into the boiler and cylinder until the water ceases flowing into the boiler, or, until the rocker arm fork 55 reaches its high limit.

In Figure 1 the water line is shown at normal. In this case the cylinder has been lowered due to the corresponding height and weight of the column of water in the cylinder, the rocker arm fork 55 has raised up to the centre contact point and the centre light goes on, indicating a normal water line. If more water is introduced into the boiler the cylinder continues to lower, the rocker arm fork 55 continues upward making a contact with each successive circuit causing each lamp in its course to light up and indicate the height of the water line.

As the water line in the boiler lowers the water in the cylinder becomes correspondingly lower and as the weight in the column of water lessens in the cylinder it raises due to the tension of the spring, the rocker arm fork 55 lowers, cutting in each lower light circuit thereby indicating the position of the water line, until the water line has reached its low limit level again as shown in Figure 2.

Any number of indicator panels may be in-

stalled and operated from one contactor panel by installing a system of wiring as shown to each indicator panel and connecting to a main wire 84. Only one wire 63 as shown is necessary for one or more indicating panels which is obvious.

It is believed that the many advantages of a boiler water line indicating device in accordance with the present invention will be readily understood, and although the preferred embodiment of the invention is as illustrated and described, it is to be understood that changes in the details of construction and in the combination and arrangement of parts may be resorted to which will fall within the scope of the invention as claimed.

What is claimed is:

1. In a water line indicating device for remotely indicating the water line of a steam boiler below said water line, a closed cylinder, flexible communication means between said cylinder and a boiler for conveying a fluid from said boiler to said cylinder, flexible communication means between said cylinder, and said boiler for relieving gas from said cylinder to said boiler, flexible means for supporting said cylinder, said flexible supporting means adapted to permit a downward movement of said closed cylinder as said fluid is conveyed to said cylinder and said gas is relieved through said gas relieving flexible communication means, indicator means, said indicator means comprising a rocker arm and a stationary panel, said rocker arm being pivotally connected intermediate of its ends to said closed cylinder, one end of said arm adapted to slide arcwise over said panel, said indicator means being provided with graduation points on said panel to indicate the relative position of said water line as the end of said arm moves over said points.

2. In a water line indicating device for remotely indicating the water line of a steam boiler below said water line, a closed cylinder, flexible communication means between said cylinder and a boiler for conveying a fluid from said cylinder to said boiler, flexible means for supporting said cylinder, said flexible supporting means adapted to permit an upward movement of said closed cylinder as said fluid is conveyed to said boiler, indicator means, said indicator means comprising a rocker arm and a stationary panel, said rocker arm being pivotally connected intermediate of its ends to said closed cylinder, one end of said arm adapted to slide arcwise over said panel, said indicator means being provided with graduation points on said panel to indicate the relative position of said water line as the end of said arm moves over said points.

3. In a water line indicating device for remotely indicating the water line of a steam boiler below said water line, a closed cylinder, flexible communication means between said cylinder and a boiler for conveying a fluid to and from said boiler and said cylinder, flexible means for supporting said cylinder, a balanced rocker arm, said cylinder pivotally connected to said rocker arm intermediate of its ends, a rigidly supported platform, pivotal supporting means for said rocker arm attached to said platform, said rocker arm pivotally attached intermediate of its ends to said pivotal supporting means, said flexible supporting means adapted to permit a downward and upward movement of said closed cylinder as said fluid is conveyed to and from said cylinder and said boiler, a stationary panel provided with indicator means adapted to permit one end of said rocker arm to slide on and contact said indicator means,

said rocker arm moving arcwise over said indicator means thereby indicating the relative position of said water line.

4. In a water line indicating device for remotely indicating the water line of a steam boiler, a closed cylinder, flexible communication means between said cylinder and a boiler for conveying a fluid from said cylinder to said boiler, flexible means for supporting said cylinder, a balanced rocker arm having on one end an electrical contact and on its opposite end a slidable adjustable counter-balancing weight, said cylinder pivotally connected to said rocker arm intermediate of its ends, a rigidly supported platform, pivotal supporting means for said rocker arm attached to said platform, said rocker arm pivotally attached intermediate of its ends to said pivotal supporting means, a contactor panel with multiple contact points attached to said platform, an indicator panel equipped with lamp sockets and electric lamps located outside of the boiler room, a system of electric wiring between said contactor panel and indicator panel, a system of wiring between said indicator panel and a source of electric current, an electrical connection between said rocker arm electrical contact and said source of electric current, said flexible supporting means adapted to permit an upward movement of said closed cylinder as said fluid is conveyed to said boiler from said cylinder causing said rocker arm electrical contact end to move downward over said contactor points on said contactor panel thereby making consecutive electrical circuits through the electric lamps on the said indicator panel enabling one to determine the height of the water line in said boiler as each electric lamp corresponding to the height of said water line lights up.

5. In a water line indicating device for remotely indicating the water line of a steam boiler, a closed cylinder located alongside of said boiler, flexible communication means between said cylinder and the boiler for conveying a fluid to and from said boiler and said cylinder, flexible means for supporting said cylinder, a balanced rocker arm, said cylinder pivotally connected to said rocker arm intermediate of its ends, a rigidly supported platform, pivotal supporting means for said rocker arm attached to said platform, said rocker arm pivotally attached intermediate of its ends to said pivotal supporting means, said flexible supporting means adapted to permit a downward and upward movement of said closed cylinder as said fluid is conveyed to and from said cylinder and said boiler causing said rocker arm to seesaw, an indicator located remote from said closed cylinder and said boiler, said indicator comprising electrical lighting circuits operated through the seesaw movement of said balanced rocker arm.

6. In a water line indicating device for remotely indicating the water line of a steam boiler comprising in combination a closed cylinder, flexible communication means between said cylinder and the boiler for conveying a fluid from said cylinder to said boiler, flexible means for supporting said cylinder, a balanced rocker arm having on one end an electrical contact and on its opposite end a slidable adjustable counter-balancing weight, said cylinder pivotally connected to said rocker arm intermediate of its ends, a rigidly supported platform, said rocker arm pivotally attached intermediate of its ends to pivotal supporting means attached to said platform, a contactor panel with multiple contact points at

tached to said platform, an indicator panel equipped with lamp sockets and electric lamps, a system of electric wiring between said contactor panel and indicator panel, a system of wiring between said indicator panel and a source of electric current, an electrical connection between said rocker arm electrical contact and said source of electric current, said flexible supporting means adapted to permit an upward movement of said closed cylinder as said fluid is con-

veyed to said boiler from said cylinder causing said rocker arm electrical contact end to move downward over said contactor points on said contactor panel thereby making consecutive electrical circuits through the electric lamps on the said indicator panel enabling one to determine the height of the water line in said boiler as each electric lamp corresponding to the height of said water line lights up.

JOSEPH R. GUILDFORD.
